APPARATUS FOR FLAME HARDENING

Richard J. Wolf, Chicago, Ill.

Application July 12, 1941, Serial No. 402,219

4 Claims. (Cl. 266—4)

This invention relates to improvements in apparatus for flame hardening, and more particularly to apparatus for the flame hardening of spur gears and the like.

In the process of flame hardening, it is desired to raise the temperature of a localized surface area of the articles to be hardened above the critical temperature of the steel thereof, and then quench the heated area in a suitable medium to impart the desired surface hardness to the metal. In such a process, the depth of hardness is controlled by the degree of heat penetration at critical temperature and the severity of the quench.

It is an object of my invention to provide an improved apparatus wherein the quenching medium may be applied to the preheated surface of the steel to properly quench the same without interfering with the application of heat thereto, and has in view the application of a source of heat and a quenching medium to the surface of the work in that order, said heat and quench and the work then being moved relatively so as to treat the work progressively upward from the lowermost portion thereof. In this manner, gravity controls the vertical limit and distribution of the quenching medium so as not to interfere with the heating process.

My invention contemplates effecting a movement of the articles being treated in relation to the flame and a quenching bath, thereby enabling the continuous treatment of a plurality of superimposed articles, and employs a multiplicity of torches or other heat sources, thereby enabling increased production in a flame hardening treatment while at the same time maintaining controlled uniformity of the treatment.

Further objects are to provide an apparatus for the purposes stated including indexing means for alignment of the torches and gears, to provide a simple and efficient mounting for the multiplicity of torches or flame devices, and to mount said torches or flame devices and their service equipment in efficient and convenient relation to a tank or container for the quenching medium.

Additional objects and advantages will become apparent from the following description taken in connection with the accompanying drawings wherein:

Fig. 1 is a top plan view of a flame hardening apparatus embodying my invention; and

Fig. 2 is a vertical sectional view thereof, taken on the line II—II of Fig. 1.

Referring to the drawings, 2 designates a cylindrical tank or container for a quenching medium

or bath 3. A hydraulic cylinder 4 is mounted centrally of the bottom of the tank for receiving a piston or plunger 5 for vertical movement of the latter centrally within the bath 3. The upper end of the plunger 5 is provided with a work-receiving table or chuck 6, rotatably supported on said plunger as by means of a bearing 7, said chuck being provided with a series of vertically extending elongated jaws 8 for receiving and supporting a plurality of spur gears 9 by the central bores or apertures of the latter.

The upper free terminals of the jaws 8 are internally threaded to receive a threaded taper plug 10 for expanding said jaws outwardly into holding engagement with the gears thereon. In this manner, a column composed of a plurality of superimposed identical gears may be mounted with their respective teeth 11 disposed in vertical alignment, and when so assembled, the gears may be treated as a unit. By controlling the supply of fluid to and from the cylinder 4, as by means of a regulating valve 12, the plunger and the plurality of gears may be raised or lowered in relation to the level of the quenching liquid or bath 3.

A pair of circular tracks 13 are concentrically disposed about the tank 2, being supported from the latter by a series of brackets 14. Movable on the tracks 13, I provide a plurality of carriages 15 mounting and supporting torches or heating devices 16. A pair of torches may be provided on each carriage 15, said torches being radially positioned with respect to the common vertical axis of the gears 9 and being slidably adjustable toward and away from the gears as by means of supporting rods 17 reciprocable in adjustable tubular supports 18 of the carriages. Also, the torches 16 are preferably pivoted at 19 at their point of connection with their respective rods 17, thereby permitting pivotal movement for alignment of the torch tips 20 with the gear teeth 11, as particularly shown in Fig. 2.

Hence, each of the pairs of torches 16 may be properly spaced for impingement of the flames thereof on opposite sides of a gear tooth 11 of the superimposed gears 9, and said pairs of torches may be moved on their circular tracks 13 upon supporting carriage wheels 21 to selectively position said pairs of torches in relation to the plurality of teeth of the gears.

In the event that the gears 9 have even numbers of teeth, the carriages 15 may be diametrically disposed on opposite sides of the tank 2, by means of locking pins 22 engageable in diametrically disposed recesses 23 in the rim or body

of the tank. Also, when treating gears having even numbers of teeth, upon diametrically locating the carriages and torches in the manner described, the chuck 6 may be rotated as by means of a handle 24 extending upwardly above the bath 3, to thereby align a selected gear tooth with said torches. A spring pressed retractable radial index finger or pawl 25 is adjustably secured over the upper edge of the tank 2 for entrance between the teeth of the positioned series of gears 9 to thereby maintain the same against rotation and in alignment with the torches.

In operation, the series of superimposed gears 9 are lowered by means of plunger 5 until the lowermost gear thereof is immediately above the surface of the quenching bath 3, and torches 16 are positioned to have their tips 20 immediately above said bath 3. Upon attaining the desired preheating by means of the torches, the hydraulic valve 12 is opened and adjusted to effect a desired lowering of the column of gears 9 into the quenching bath, whereby the selected and aligned teeth of the respective gears are continuously and uniformly heated and quenched. As the selected teeth of the uppermost gear are quenched, the column of gears is again elevated to starting position at the surface of the bath, said column rotated and indexed by the device 25 for alignment of other teeth with the torches, and the heating and quenching operation is repeated as before. Hence, the foregoing cycle is repeated until each of the aligned series of gear teeth of the column of gears has been subjected to the hardening treatment.

When it is desired to harden identical gears 9 having uneven numbers of teeth, the indexing finger 25 is employed as before, and the pairs of torches adjusted for proper convergence upon opposite faces of the selected gear teeth. However, since the carriages 15 will no longer be diametrically opposed, the same are provided with track clamps 26 for securing the carriages and torches to the tracks 13 in selected adjustment about the column of gears.

For the purpose of supplying the torches 16, arcuate oxygen manifolds 27 and acetylene manifolds 28 are mounted on the under sides of the brackets 14, said manifolds having a plurality of spaced hose cocks 29 for connection with the torches 16 as by flexible conduits or hoses 30. Supply pipes 31 and 32 are provided for respectively conducting oxygen and acetylene to the arcuate manifolds 27 and 28.

Thus, by the apparatus of my invention, I am enabled to flame harden a plurality of identical gears at one time, thereby effecting uniform hardening treatment. My improved apparatus provides a positive and simple control for carrying out the heating and quenching operations in order to maintain the desired uniformity of heat treatment.

Various changes and modifications are contemplated within the scope of the following claims.

I claim:

1. Apparatus for flame hardening a plurality of identical spur gears and the like, including a quenching tank, a chuck for supporting a vertically aligned column of said gears centrally of the tank, a trackway about the tank, carriages movable on said trackway, each of said carriages having a pair of flame devices thereon, means for adjustably positioning the flame devices to direct the flames thereof inwardly toward the gear column and immediately above the level of the quenching liquid in the tank, and means for lowering the chuck and gear column into the quenching liquid.

2. Apparatus for flame hardening a plurality of identical spur gears and the like, including a quenching tank, a chuck for supporting a vertically aligned column of said gears centrally of the tank, a trackway about the tank, carriages movable on said trackway, each of said carriages having a pair of flame devices thereon, means for adjustably positioning the flame devices to direct the flames thereof inwardly toward the gear column and immediately above the level of the quenching liquid in the tank, means for lowering the chuck and gear column into the quenching liquid, and indexing means engaging the gear teeth for guiding the lowering of the gear column in accordance with the alignment of the teeth of the respective gears.

3. Apparatus for flame hardening a plurality of identical spur gears and the like, including a quenching tank, a chuck for supporting an aligned column of said gears centrally of the tank with the respective teeth thereof in alignment, a trackway about the tank, a carriage movable on said trackway, a pair of flame devices mounted on the carriage and directed inwardly toward a selected tooth of the gear column immediately above the level of the quenching liquid in the tank, means for lowering the chuck and gear column into the quenching liquid, and indexing means adjustably engaging the teeth of the gear column to maintain alignment of the torches and selected gear teeth of the successive gears as the column thereof is lowered.

4. Apparatus for flame hardening a plurality of identical spur gears and the like each having a central bore, including a chuck having jaws entered in said bores for supporting a column of said gears with the respective teeth thereof in alignment, a quenching bath, a pair of adjacent related flame devices directed convergently inward toward a selected tooth of the gear column immediately above the quenching bath, means supporting said flame devices for adjustable travel thereof circumferentially about the column, means for lowering the chuck and gear column into the quenching bath, and a stationary index finger slidably engaging the gear teeth for maintaining alignment of like teeth of the gears with the flame devices during the lowering of said gear column.

RICHARD J. WOLF.
